UNITED STATES PATENT OFFICE.

LOUIS HELFRITZSCH, OF BERLIN, GERMANY.

AUTOMATIC SMALL-ARMS.

No. 800,103.

Specification of Letters Patent.

Patented Sept. 19, 1905.

Application filed May 23, 1902. Serial No. 108,700.

To all whom it may concern:

Be it known that I, LOUIS HELFRITZSCH, engineer, a subject of the German Emperor, residing at Tempelhofer Ufer No. 10, Berlin, 5 in the Empire of Germany, have invented certain new and useful Automatic Small-Arms, of which the following is a specification, reference being had to the drawings hereunto annexed and to the letters marked thereon.

10 This invention relates to an automatic recoil-operated breech-loading firearm having a sliding barrel and is an improvement upon the type of arm covered by my United States Patent No. 675,999.

15 The improvement herein described and claimed presents this feature: that during the rearward motion of the barrel only the breech-bolt, which is provided with straight locking-nipples, performs a partial revolution within the barrel enlargement, thus disengaging the nipples, while the independent movement of the breech-bolt effects the release of the nipples from the grooves of the barrel enlargement, whereby the breech-closure 20 is unlocked. There is further provided in this improved gun a special coupling arrangement to provide for single loading, whereby as the breech-bolt approaches the end of the path it is designed to traverse the

25 barrel is automatically engaged, so that a means is thus afforded for securing it in its rearmost position, the object being that the breech-bolt as it springs forward may find the barrel in the proper position for locking.

30

35 My improved firearm is represented in the accompanying drawings, in which—

Figure 1 is a side view, partly in section, showing the arm with the breech locked. Fig. 2 shows the position of the breech after 40 the barrel has moved to its rearmost position and when the breech-bolt has already commenced its independent return movement. Fig. 3 shows the position of the parts with the breech-bolt in the rearmost position, the 45 barrel having in the meantime moved a short distance forward. Fig. 4 represents the frame and coupling-rod seen from the opposite side and partly in section. Fig. 5 is a cross-section on line A B, Fig. 2. Fig. 6 is 50 a cross-section on line C D, Fig. 4; and Fig. 7 is an elevation of the rail or rod which serves to guide the breech-bolt seen from the opposite side to that shown in Fig. 4.

Referring to the drawings and the mode of 55 operation more in detail, the barrel-case *b*, which surrounds or envelops the barrel *c* and

receives the pressure-spring, (not shown,) is at its enlarged rearward part screwed onto the stationary frame *a*. This barrel-case *b* at the same time serves to guide the barrel *c*, the rear end of which terminates in the barrel-enlargement *d*, wherein the barrel-nipples, which form abutments or stops for the breech-bolt-locking nipples, are situated. Both the barrel enlargement *d* and the breech-bolt *k* are provided with straight nipples extending practically parallel to the longitudinal axis of the breech-bolt and barrel. Hence in the weapon as herein described the locking and unlocking operations as the breech-closure is being locked or released, as the case may be, take place as follows: During the joint rearward movement of the barrel and breech-bolt under the influence of the recoil only the latter performs a partial revolution, whereby its nipples *e* by the time the barrel has reached its rearmost position come out of contact with the barrel-nipples *d* and in line with the corresponding grooves or passages *d'*, situated between the said barrel-nipples. Hence the breech-bolt *k* is only enabled (after the barrel has completed its rearward movement) to begin to move away from the barrel, in doing which, as a result of the shape of the slot *k'*, sliding upon the guide-piece *i*, it performs a rectilinear rearward movement and as it does so, together with its nipples, passes through and becomes disengaged from the grooves *d'*. Thus by the improvement just described the arrangement of the nipples constitutes what may be termed a "positive" as distinguished from a "friction" breech-lock. In the form of weapon represented in the drawings—namely, a rifle—there is further provided on the barrel an arresting device, serving to render the locking secure, whereby in automatic firing the barrel is automatically retained in the position to which it has been drawn back until the breech-bolt has sprung forward again into the locking position. This arresting device consists of an arresting-lever *r* and an abutment-lever *m*, the lower arm *n* of which as the barrel recedes impinges upon the nose *o*, projecting from the front wall of the magazine, and thereby turns the lever *m* into the arresting position, in which the forward arm *s* engages in a recess in the barrel-case, Fig. 2, and thereby prevents the return of the barrel until the breech-bolt as it springs forward strikes with its forward surface the upper arm *m* of the abutment-lever, whereby

this lever itself and the barrel are released. (See Fig. 1.) At the same time an acceleration of the rearward movement of the breech-bolt after its release is insured by the fact that as the arm n impinges on the projection or stop o the lever m not only moves the lever r into the locked position, but with its upper arm m strikes the shoulder of the breech-bolt, the effect of this stroke being at the same time to facilitate the extraction of the empty cartridge-case. In single-loading the breech-bolt is moved back by what is known as a "guiding-rail" p , fitted with a knob q , which through the medium of a screwed pin l engages in a circular slot h in the breech-bolt and which normally is retained in the forward position in which it is depicted in Fig. 4 by a spring v , arranged in a lateral casing u and acting upon a projection g of the rail through the medium of a rod w , and in order to render the operation of the breech-closure during the locking process more reliable a special coupling device y is provided, the rearward end z of which passes up into the casing u and against which the spring v exercises pressure, while its forward end is attached to the projection x of the barrel. The object of this coupling-piece is automatically to carry the barrel with it, and thereby to enable it to be locked in its rearmost position as the breech-bolt comes near to the end of its course. Whereas in automatic loading, owing to the great force of the recoil, under which the barrel receives the shock or impact, the said barrel becomes locked by the arresting mechanism r s m n o , just described, without any difficulty, it has been found in single-loading that the more even effort of the hand is not sufficient to drive the barrel back into its rearmost position, and thereby to cause it to be locked in that position as the breech-bolt begins its independent movement. Hence in single-loading the barrel immediately after it has been disengaged from the breech-bolt generally springs forward again without having had the opportunity of becoming locked as a result of the impact of the lever end n upon the stationary stop o . It is this deficiency which it is the object of the coupling device y to supply, for, owing to the provision of this device, when the breech-bolt has nearly reached the end of its course the barrel is drawn along by the compressed spring v and through the intermediate agency of the coupling-rod y , thereby enabling the arresting mechanism to come into operation and to lock the barrel in its rearmost position.

What I claim is—

1. In a firearm, the combination, with a barrel mounted for sliding longitudinal movement only, a breech-bolt, interlocking nipples and grooves connecting the two, means for unlocking the one from the other and permitting the breech-bolt further independent

movement, of an arresting-lever mounted upon the movable barrel portion, one end of said lever arranged to engage a fixed portion of the arm to secure the barrel in its rearward position, a second lever operated by the recoil for throwing the first lever into operation, and means for releasing the same.

2. In a firearm, the combination, with a sliding barrel, a breech-bolt, interlocking nipples and grooves connecting the two, means for unlocking the one from the other and permitting the breech-bolt further independent movement, of an arresting-lever, one end of said lever arranged to secure the barrel in its rearward position, a trip-lever mounted adjacent to the arresting-lever, one end of the trip-lever engaging the arresting-lever to throw the same into operation, and the other end of the trip-lever engaged by the forward movement of the breech-bolt to throw the arresting-lever out of operation.

3. In a firearm, the combination, with a sliding barrel, a breech-bolt, interlocking nipples and grooves connecting the two, means for unlocking the one from the other and permitting the breech-bolt further independent movement, of an arresting-lever mounted upon the movable barrel portion, one end of said lever adapted to engage a fixed portion of the arm and secure the barrel in its rearward position, a trip-lever mounted adjacent to the arresting-lever, one end of the trip-lever engaging the arresting-lever to throw the same into operation, and the other end of the trip-lever engaged by the forward movement of the breech-bolt to throw the arresting-lever out of operation.

4. In a firearm, the combination, with a sliding barrel, a breech-bolt, interlocking nipples and grooves connecting the two, means for unlocking the one from the other and permitting the breech-bolt further independent movement, of an arresting-lever mounted upon the movable barrel portion, one end of said lever adapted to engage a fixed portion of the arm and secure the barrel in its rearward position, a trip-lever mounted upon said movable barrel portion adjacent to the arresting-lever, a nose carried by a fixed portion of the arm to contact with the trip-lever and force one arm of said lever into operative engagement with the arresting-lever, and the other arm of the trip-lever engaged by the breech-bolt in its forward movement to release the arresting-lever.

5. In a firearm, the combination, with a sliding barrel, a breech-bolt, interlocking nipples and grooves connecting the barrel and breech-bolt, means for disconnecting the two and permitting the breech-bolt further independent movement, means for retracting the breech-bolt, a projection accompanying the bolt in its independent movement, a coupling device attached at one end to the barrel and at the other end provided with a projection,

and a spring acting upon the two projections, whereby, throughout the independent movement of the breech-bolt tension will be exerted upon the barrel.

- 5 6. In a firearm, the combination, with a sliding barrel, a breech-bolt, interlocking nipples and grooves, means for disconnecting the barrel and breech-bolt, a guide-rail connected with the breech-bolt, an operating-knob carried by said guide-rail, a projection carried by the rail, a spring inclosed in a casing acting upon said projection, a projection carried by the barrel, a coupling device attached at its forward end to the projection on the barrel, and an extension on the rear end of said coupling device entering the said casing and engaging the spring, whereby when the breech-bolt is manually retracted the barrel is automatically carried to its rearmost position.
- 10 7. In a firearm, the combination, with a barrel mounted for sliding longitudinal movement only, a breech-bolt, interlocking nipples and interposed longitudinal grooves connect-

ing the barrel and breech-bolt, and means 25 consisting of a deflected slot and a lug for disconnecting the barrel and breech-bolt and permitting independent movement of the latter, of yielding means connecting the breech-bolt with the barrel whereby, throughout the 30 independent movement of the breech-bolt, tension will be exerted upon the barrel, an arresting-lever adapted to engage and hold the barrel in its rearmost position during the further independent movement of the breech-bolt, a trip-lever mounted adjacent to the arresting-lever, means for causing one end of the trip-lever to engage the arresting-lever to throw the same into operation, and the other end of the trip-lever engaged by the forward 35 movement of the breech-bolt to throw the arresting-lever out of operation.

In witness whereof I have set my hand in the presence of two witnesses.

LOUIS HELLFRITZSCH.
